DESIGN FOR A TEXTILE FABRIC

Charles W. Clackett and Alfred Max Werner,
New York, N. Y.

Application July 10, 1940, Serial No. 93,545

Term of patent 3½ years

To all whom it may concern:

Be it known that we, Charles W. Clackett and Alfred Max Werner, citizens of the United States, residing in New York city, in the county of New York and State of New York, have invented a new, original, and ornamental Design for a Textile Fabric, of which the following is a specification, reference being had to the accompanying drawings, forming part thereof.

Fig. 1 is a plan view of a textile fabric showing our design, and

Fig. 2 is the reverse side thereof.

Fig. 3 is an enlarged fragmentary view of Figure 1 showing the repeat lengthwise.

We claim:

The ornamental design for a textile fabric, substantially as shown.

CHARLES W. CLACKETT.
ALFRED MAX WERNER.
